CAMERA TRIPOD

Courtney A. Leubner, Oak Brook, Ill., assignor to
Quick-Set, Incorporated

Filed Sept. 4, 1969, Ser. No. 19,020

Term of patent 14 years

Int. Cl. D16—05

U.S. Cl. D61—1

FIG. 1 is a perspective view of the camera tripod showing my new design;

FIG. 2 is a perspective view of the camera tripod illustrated in FIG. 1 rotated approximately one hundred eighty degrees;

FIG. 3 is a fragmentary enlarged perspective view of the camera tripod of FIG. 1 showing another possible orientation of the camera tripod head elements; and

FIG. 4 is a fragmentary enlarged perspective view of the camera tripod of FIG. 1 showing the camera tripod head from an angle of approximately forty-five degrees above the horizontal with the tripod head elements in a different orientation.

I claim:

The ornamental design for a camera tripod, as shown and described.
